US00D865525S

(12) **United States Design Patent** (10) **Patent No.:** **US D865,525 S**
Staab et al. (45) **Date of Patent:** **** Nov. 5, 2019**

(54) **COSMETIC CONTAINER**

- (71) Applicant: **Mary Kay Inc.**, Addison, TX (US)
- (72) Inventors: **Jenny DeMarco Staab**, Addison, TX (US); **Tammy Schriewer**, Addison, TX (US)
- (73) Assignee: **Mary Kay Inc.**, Addison, TX (US)
- (**) Term: **15 Years**
- (21) Appl. No.: **29/680,112**
- (22) Filed: **Feb. 13, 2019**

Related U.S. Application Data

- (60) Continuation of application No. 29/610,191, filed on Jul. 10, 2017, now Pat. No. Des. 844,441, which is a continuation of application No. 29/537,050, filed on Aug. 21, 2015, now Pat. No. Des. 795,075, which is a division of application No. 29/502,064, filed on Sep. 11, 2014, now Pat. No. Des. 739,739.
